Primary Examiner — Cynthia Ramirez(74) *Attorney, Agent, or Firm* — Allen, Dyer, Doppelt + Gilchrist, PA(57) **CLAIM**

The ornamental design for a part for a pallet, as shown and described.

DESCRIPTION

FIG. 1 is an upper perspective view of a part for a pallet showing our new design;

FIG. 2 is a bottom view thereof;

FIG. 3 is a front view thereof;

FIG. 4 is a left side view thereof;

FIG. 5 is a rear view thereof;

FIG. 6 is a right side view thereof; and,

FIG. 7 is a top view thereof.

The broken lines in the drawings show portions of the part for a pallet, which form no part of the claimed design.
